UNITED STATES PATENT OFFICE.

AARON C. HORN, OF NEW YORK, N. Y.

SPOT-GROUND.

1,347,633.

Specification of Letters Patent. Patented July 27, 1920.

Application filed March 14, 1917. Serial No. 154,711.

To all whom it may concern:

Be it known that I, AARON C. HORN, a citizen of the United States, and a resident of New York city, in the county of New York and State of New York, have invented certain new and useful Improvements in Spot-Grounds, of which the following is a specification.

This invention relates in general to what is known in the building art as "grounds" or "spot grounds," and in particular to screeds or framing pieces adapted to form a basis for other structure, and which may be effectively and readily attached at any desired point to a wall, partition or floor.

In fire-proof building construction, it becomes necessary to fasten ground strips to a concrete, plaster, tile or the like wall, partition or floor. The usual nail or screw attaching means clearly cannot be availed of with advantage in such cases and the direct attachment of these strips has been limited, as for example, to the location of the joints between blocks. Recourse has been had to several methods for providing suitable points of attachment for the grounds, but these always involve extra time, labor and material and substantially increase the cost of construction. One method commonly used is that of digging out mortar joints into which the grounds are driven. But this requires much additional time and labor and consequent extra cost.

Cement compositions such as plaster of Paris have been used to attach grounds to desired points on the wall or partition. But for this purpose the grounds have hitherto been made with a metal base adapted to be embedded in the cement. This metal construction presents many practical difficulties. Thus, the base having a smooth surface, the bond between it and the plaster is not sufficiently strong. Furthermore, water is always needed in building construction to give plasticity to the materials used. Therefore, there is always present in the structure some moisture which together with the oxygen will corrode the metal plate and cause it to wear away and eventually penetrate the wooden ground and cause it to deteriorate, while the bond between the metal plate and the adhesive means ultimately fails completely. An attempt has been made to increase the bond between the metal base

and the plaster by perforating the former and allowing the cement composition to pass therethrough. But this involves a material increase in cost of manufacture of the metal base, and as a whole the metal backed ground may be said to be too expensive for the purpose sought to be attained thereby, in view of its aforementioned disadvantages.

One object, therefore, of this invention is to provide a spot ground which shall be effectively and readily attachable to any wall, floor or partition at any desired point thereon.

Another object of this invention is to provide a spot ground of this character which shall be free from the disadvantages of the metal backed ground and yet cheap to manufacture.

A further object of this invention is to provide a spot ground of the character described which shall be durable, neat and compact and easily handled and shipped.

Further objects and advantages of this invention will appear from the detailed description and the features of novelty will be particularly pointed out in the claims.

In the accompanying drawings forming a part of this specification,

Figure 1 is a broken away view showing the improved spot ground in use as a framing piece for the attachment thereto of wooden building parts, such as molding and the like structure.

Fig. 2 is an enlarged broken away sectional view of one form of the improved spot ground.

Fig. 3 shows a modified form of the spot ground in use as an improved furring strip for waterproofing.

Figs. 4, 5, 6 and 7 show further modified embodiments of this invention.

Referring particularly to the drawings, my improved ground is seen to consist of a block 10 made of any material into which nails or screws may be driven and is formed with a face 11 to which may be nailed a facing strip, molding or the like wooden building part 12 after the plastering 13 has been applied to the wall. The block is further formed with an enlarged base 14 to which is attached a strip of some suitable waterproofing material 15. In the particular construction shown in the drawing, this waterproofing strip is attached to the base 110 of the screed by some suitable adhesive means such as a coating 16 of some asphal-

tic cement and is composed preferably of several layers 17 of felt or fabric saturated with a hot bituminous compound and cemented together to secure structural strength. This construction waterproofs the spot ground from the wall or other structure 18 to which it is attached and thus preserves it from deterioration. As will be clear from the drawing, the outer surface 10 of the waterproofing strip 15 is coated with a layer of quartz or silica preferably made up of pebbles 19, and the screed thus presents a rough irregular surface to the adhesive means 20, such as plaster of Paris, whereby it is secured to the wall or other structure at any desired point. As will be readily understood, the bond between the cement 20 and the waterproofing strip is materially increased by the irregularities in 20 the surface 19 and thus the screed may be positively and firmly secured at any desired point.

In the modified form shown in Figs. 5 and 6, the waterproofing layer is circular in 25 form and has portions 21 extending beyond the base both faces of which are pebbled. This construction presents a larger bonding area and permits of the formation of the perforations 22 in said extended portions 30 through which some of the cement may be squeezed when the screed is pressed thereto, to aid in more effectively securing the screed therein, by the spreading of the cement over the under face of the waterproofing strip.

In another modified form shown in Fig. 4, the base 12' is circular and has perforations 23 to register with the smaller perforations 22' in the circular waterproofing 40 layer attached thereto.

In still another modified form shown in Fig. 7, the sides of the screed are formed with dove-tail recesses 24, into which the plastering 13 enters to form a wedge to aid 45 in more firmly securing the screed. In this form the waterproofing layer extends around the sides of the screed up to the dove-tail recesses as shown at 25 in the figure.

50 In Fig. 3 a form of screed is shown which is specially adapted to serve as a furring strip when it is desired to waterproof inner plastering 26 from an outer exposed wall or other structure 27. The screed for this 55 purpose has additional waterproofing material 28 on its sides and exposes only one face to which the lath or plaster board 29 may be nailed.

A furring strip constructed in this way 60 is, of course, more durable and clearly effects better superstructural waterproofing than that hitherto had with the ordinary metal covered wood furring strips to which all the objections raised against metal 65 backed screeds apply with even greater

force, due to the presence of moisture in much larger quantities.

Having thus described my invention, I claim as new and desire to secure by Letters Patent:—

70 1. A spot ground for concrete or similar floor, wall, or partition construction comprising a fiber block, said fiber block formed with a face for nailing wooden building parts thereto, and having an enlarged base 75 and a nonmetallic waterproofing strip attached thereto, said strip having an exposed rough pebbled surface.

2. In combination with a concrete or similar supporting structure, and adhesive means 80 disposed at any desired point thereon, a spot ground adapted to be attached to said structure by said adhesive means, said spot ground comprising a fiber block and a strip of nonmetallic waterproofing attached 85 thereto along one face of the former, there being a pebble layer attached to the other face thereof whereby the latter presents a rough surface to said adhesive means to form a firm bond therewith. 90

3. In combination with a concrete or similar supporting structure, and adhesive means disposed at any desired point thereon, a spot ground adapted to be attached to said structure by said adhesive means, said spot 95 ground comprising a fiber block, said fiber block formed with a face for nailing auxiliary building parts thereto and having an enlarged base portion and a nonmetallic waterproofing strip attached thereto and extending beyond the sides of said base, the extended portions of said strip being provided with perforations for the passage of said adhesive means therethrough, and an outer layer of small hard particles on each 100 face thereof to present an irregular surface to said adhesive means for forming a firm bond with said adhesive means. 105

4. In combination with a concrete or similar supporting structure and adhesive means 110 disposed at any desired point thereon, a spot ground adapted to be attached to said structure by said adhesive means, said spot ground comprising a fiber block, said fiber block formed with a face for nailing wooden 115 building parts thereto and having an enlarged base portion and a nonmetallic waterproofing strip attached thereto, said waterproofing strip and base portion having perforations therein for the passage of said adhesive means therethrough, and an outer layer of small hard particles on each face 120 thereof to present an irregular surface to said adhesive means for forming a firm bond with said adhesive means. 125

5. In superstructural waterproofing, in combination with an exposed structure, an intermediate lining strip and an inner plastered layer to be waterproofed from said exposed structure by the furring process, a 130

furring strip adapted to be secured between said structure and lining strip to form an air space therebetween, said furring strip comprising a fiber block covered with a layer of 5 waterproofing material, the outer face thereof being coated with a layer of small hard particles to present a rough surface, one face of said block remaining exposed for the attachment of the lining strip and plastered 10 layer thereto in spaced relation to said exposed structure.

6. A spot ground for building construction comprising a fiber block formed with a face for nailing wooden building parts

thereto and having an enlarged base and a 15 water proof strip attached thereto, said strip comprising layers of fabric saturated with a bituminous compound and cemented together, the outer layer having an exposed rough pebbled surface.

Signed at New York city, in the county of New York, and State of New York, this 20 tenth day of March A. D. 1917.
